UNITED STATES PATENT OFFICE.

SILVIO SCHEWCZIK, OF SAN REMO, ITALY.

DRYING PLANT FOR TEXTILE FABRICS.

1,072,512.

Specification of Letters Patent.

Patented Sept. 9, 1913.

Application filed July 3, 1906. Serial No. 324,606.

To all whom it may concern:

Be it known that I, SILVIO SCHEWCZIK, a subject of the German Emperor, residing at San Remo, Italy, have invented certain new and useful Improvements in Drying Plants for Textile Fabrics, of which the following is a specification.

The object of the present invention relates to improvements in drying apparatus heated by steam or any other suitable medium and which are mainly used for the drying of textile fabrics and other woven fabrics.

The object of invention aimed at is to increase the heating surface of the heating plates in such drying apparatus as well as to increase their effect by providing an air-circulation on their surface.

The novelty of the invention consists mainly in providing the plates with perforations, so that the inner walls of the same will bear forth heat also and furthermore allow of a more complete circulation of the air in the drying apparatus around the heating plates, through the same, and the textile fabric.

In the drawings the object of the invention is illustrated in several constructional forms as well as in its various applications for the drying of woven fabrics.

Figures 1, 3 and 5 are top views of the plate in three different forms; Figs. 2, 4 and 6 are each a cross section of the plate as per Figs. 1, 3 and 5; Figs. 7, 8, 9 and 10 show the use of the plate for drying purposes in frames, hot flues, etc., wherein, Fig. 7 illustrates such a drying device in side view with the shell removed, and the plates, one of which is shown in section, are mounted horizontally; Fig. 8 shows the same drying device in transverse section with the shell removed; Fig. 9 also represents a side view of the drying device with removed shell, in which the plates are arranged vertically and Fig. 10 shows a transverse section of the last mentioned arrangement with removed shell.

The new drier is constructed of two steel plates which form a hollow chamber. In the interior of the chamber baffle plates form, in the usual manner, the channels for the steam circulation. The two side plates *a* are fastened to each other by means of the edge-bars *b* and the baffle plates *c* by means of rivets or the like. The edge or curb-bars *b* are provided at suitable places with steam inlet and outlet nozzles *d*.

To form the air passages in the drier, apertures in the side plates *a* are cut out in alinement with each other (Figs. 1 and 2) and side walls are provided for the air passages, extending across the steam chamber, as for instance by short sections of pipe *f* inserted between the two plates and communicating with said apertures. These pipe sections *f* are highly heated by the steam circulation around them and between the plates. In Figs. 3, 4, 5 and 6 the perforations are formed in the following manner: The plates *a* are, where the perforations are to be struck up inwardly in such a manner that two corresponding flanges extending inwardly from the surface plates *a* overlap, and are fastened together by electric welding or other suitable means. The baffle plates *c* which form the steam channels in the described plates can be arranged in a straight form between the rows of perforations (Figs. 1 and 3) or can be curved (Fig. 5). The perforations can have any desired form.

The new drier plates serve principally, as before mentioned, for drying textile-fabric bands, of woven goods and the like and the mode of working of same is explained by Figs. 7 to 10. The shown drying plant consists in this instance of machine frames *g* the adjustable warp-supports *h* adjusted by the right and left hand threaded screws *i* which are mounted in the frame *g*, the shell *k* which incloses the drying device, and the reels *l* over which the textile fabric bands are conducted. In place of the old heretofore used solid drier plates between the bands, the new drier plates *a* described above, are now used. The same reach from one side of the shell *k* to the other and divide the drying apparatus in as many compartments as plates are used. Through a nozzle *m* in the bottom of the drying apparatus an air current is applied by pressure and taken off at the nozzle *n* in the top of the apparatus.

In using the new plate *a* with its perforations *f* the air current, which passes through the perforations *f*, is supplied with fresh heat and it is given the possibility to penetrate the web of textile fabric in a more or less vertical direction without any harm to the same. The air current is distributed by means of the perforated plates evenly in the whole compartment in such a manner that it penetrates the textile fabric without blowing through it and thereby causing the

removing of any dressing that might have been applied thereto. By means of a separate heating of the individual heating plates a any desired distribution of warmth or heat 5 can be effected.

I claim:

1. A drier for textile fabrics comprising a frame, metallic plates secured on opposite sides of said frame forming therewith a steam tight chamber, means for supplying steam for said chamber, said metallic plates having oppositely disposed apertures, and tubular connections between said apertures forming air passages through the steam chamber, baffle plates between said metallic plates, dividing said chamber into a plurality of compartments each having a row of said tubular connections, passage-ways between said baffle plates and said frame arranged alternately at one end and the other of the frame, whereby a zig-zag course will be given the passing steam.
2. A drying apparatus for textile fabrics having a housing, a plurality of rollers, an endless band passing around said rollers

for carrying the textile fabrics, and means for moving said band, a plurality of horizontal shelves in the housing and a plurality of driers supported by said shelves; said driers each comprising a frame, metallic plates secured on opposite sides of said frame forming therewith a steam tight chamber, means for supplying steam for said chamber, said metallic plates having oppositely disposed apertures, and tubular connections between said apertures forming air passages through the steam chamber, baffle plates between said metallic plates, dividing said chamber into a plurality of compartments each having a row of said tubular connections, passage-ways between said baffle plates and said frame, arranged alternately at one end and the other of the frame whereby a zig-zag course will be given the passing steam.

SILVIO SCHEWCZIK. [L.S.]
